(57) **CLAIM**

The ornamental design for a smoking waste container, as shown and described.

DESCRIPTION

FIG. 1 is a top frontal perspective view of a smoking waste container according to our new design;

FIG. 2 is a front view of the smoking waste container shown in FIG. 1;

FIG. 3 is a back view of the smoking waste container shown in FIG. 1;

FIG. 4 is a left side view of the smoking waste container shown in FIG. 1;

FIG. 5 is a right side view of the smoking waste container shown in FIG. 1;

FIG. 6 is a top view of the smoking waste container shown in FIG. 1; and,

FIG. 7 is a bottom view of the smoking waste container shown in FIG. 1.

The broken lines immediately adjacent the shaded areas represent the bounds of the claim and all other broken lines are for illustrative purposes only. None of the broken lines form a part of the claimed design.
